UNITED STATES PATENT OFFICE.

JOHN MITCHELL, OF ROCHESTER, NEW YORK, ASSIGNOR TO THE CLARK'S COKING AND SMOKELESS FURNACE COMPANY, OF SAME PLACE.

FURNACE.

SPECIFICATION forming part of Letters Patent No. 415,679, dated November 19, 1889.

Application filed February 11, 1889. Serial No. 299,486. (No model.)

To all whom it may concern:

Be it known that I, JOHN MITCHELL, of Rochester, county of Monroe, State of New York, have invented an Improvement in Coking-Furnaces, of which the following description, in connection with the accompanying drawings, is a specification, like letters on the drawings representing like parts.

This invention relates to furnaces of that class in which soft or bituminous coal is consumed, and wherein the volatile products freed from the coal are ignited and a maximum amount of heat obtained from a minimum amount of coal.

15 Prior to my present invention I am aware that furnaces provided with a boiler have been constructed in which the soft or bituminous coal is consumed in a coking-oven within the said furnace, the said coking-oven being 20 provided with a top arch or roof and with a flue connecting the said coking-oven with the ash-pit of the main combustion-chamber.

With the furnaces constructed as above described the heat generated in the coking-oven 25 is confined therein by the top arch or flue of the said oven, so that the said heat is caused to pass through the flues into the main combustion-chamber before being brought in contact with the boiler to be heated.

30 One feature of my present invention consists in constructing the coking-ovens as will be described, whereby the boiler is exposed to the direct action of the heat in the coking-oven.

35 Another feature of my invention consists in a novel construction of hearth by which the said walls of the coking-ovens are protected from intense heat, thereby prolonging the life of the same.

40 My invention therefore consists, essentially, in the furnace provided with grate-bars, a boiler supported by said furnace, a transverse wall a , and a wall a' , extended to the said transverse wall and forming a coking-oven and a combustion-chamber, a wall or 45 slab in the combustion-chamber to form a passage b' , a flue or passage b in the wall a' to connect the coking-oven with the passage b' , and an exit-flue in the transverse wall, substantially as will be described.

50 Other features of my invention will be

pointed out in the claims at the end of this specification.

Figure 1 in section and elevation shows a furnace provided with a boiler and embodying my invention. Fig. 2 is a longitudinal section of the furnace shown in Fig. 1, taken on line x x , Fig. 1; Fig. 3, a transverse section of the furnace shown in Fig. 1, taken on line y y ; and Fig. 4, a transverse section of the 60 furnace shown in Fig. 1, taken on line z z .

The furnace-walls A , sustaining the boiler A' , may be of any usual or well-known construction.

The furnace is provided at its rear end with 65 a transverse wall a and is divided longitudinally by walls a' into two coking-ovens a^3 , one at each side of the furnace, and a central chamber a^4 .

Each coking-oven a^3 is provided substantially near its center, as herein shown, with a bridge-wall a^5 , extended to the bottom of the furnace and supporting one end of grate-bars a^6 , having their other ends supported, as shown, by the front plate a^7 of the furnace. 75 Below the grate-bars a^6 is formed an ash-pit a^8 , to which access may be had by a door a^9 in the front end of the furnace; the side wall of the said ash-pit (marked a^9) forming the lower front portion of the side wall a' of a 80 coking-oven, the ash-pit wall a^9 being made wider than that portion of the wall a' above the grate-bars, for a purpose to be hereinafter described.

Each side wall a' at the rear end of the furnace forms with the transverse wall a a flue or passage b , which connects the coking-oven a^3 with a central chamber b' , (see Fig. 4,) formed by one or more slabs b^1 , supported by the walls a' and extended from the wall a to 90 the bridge-wall a^5 . The side walls a^9 of the ash-pit support grate-bars b^2 , (see Fig. 4,) the said grate-bars and slab dividing the central spaces between the coking-oven into two chambers b^3 b^4 .

The transverse wall a forms with the rear wall of the furnace a flue or passage b^5 , and the said transverse wall is provided with an opening to connect the chamber b^3 with the said flue or passage, the said opening being 100 controlled by a suitable damper b^6 , which is herein shown as operated by a handle b^7 at

one side of the furnace; but it may be operated through any usual or suitable mechanism from the front of the furnace.

Access may be had to the coking-oven a^3 5 and to the chamber b^3 through doors $c c'$, respectively, and to the chamber b' through the door c^2 .

The side wall a' of each coking-oven, at its front end or at the grate-bars a^6 , is preferably 10 made of independent slabs or blocks d , arched to form a passage or opening d' , through which a gaseous flame from the coking-oven may pass into the central chamber b^3 .

It will be noticed that the boiler A' forms, 15 as it were, the roof of the coking-ovens and of the central chamber b^3 , the side walls a' of the said coking-ovens being extended to the said boiler and serving as a support for the same at its under side within the furnace.

20 In the operation of my improved furnace the soft or bituminous coal or other material to be consumed is placed on the grate-bars within the coking-ovens a^3 and ignited. The air to support combustion is admitted through 25 the door a^8 of the ash-pit a^{17} of the coking-oven and passes up through the grate-bars and through the material thereon, carrying with it the volatile products of the coal liberated by the heat generated by the lower layer 30 or portion of the coal resting upon the grate-bars. The volatile products pass through the opening b in the wall a' into the flue or passage b' below the slabs b^{12} and the grate-bars, and thence up through the grate-bars into the 35 chamber or passage b^3 , where they meet the gaseous flame issuing from the coking-ovens through the openings d' and are consumed, the products of combustion passing from the chamber b^3 through the opening in 40 the transverse wall a into the passage or flue b^5 , and thence through the boiler to the chimney, the valve or damper b^6 being open. The heat generated by the combustion of the volatile products at that point where the said 45 volatile products commingle or meet with the gaseous flame is intense, and to remove the meeting-point of the two gases or flames from the arch of the wall a' the wall a^9 is made wider, so that as the volatile products 50 pass up by the side wall a^9 through the grate-bars b^2 they do not strike against the bricks or slabs of the arch d , but meet with the gaseous flame issuing from the passage d' away from the said arch. In this manner the 55 life of the arch d and of the wall a' is very materially lengthened.

It will be noticed that the heat generated in the coking-ovens is not confined to its front end, but is distributed throughout the said ovens and comes in contact with the boiler 60 throughout its length, thus increasing the efficiency of the furnace for the purpose of evaporation, as well as obviating burning out of the side wall of the coking-oven.

As substantially all the heat generated by 65 the consumption of the bituminous coal in the coking-oven is utilized to heat the boiler, the draft, and thereby the intensity of the flame and of the heat generated in the furnace, may be regulated by the doors in the 70 front wall of the furnace, and also by the valve or damper b^6 .

I claim—

1. The furnace provided with grate-bars, a boiler supported by said furnace, a transverse wall a , a wall a' , extended to the said transverse wall and forming a coking-oven and a combustion-chamber, a wall or slab in the combustion-chamber to form a passage b' , a flue or passage b in the wall a' to connect the coking-oven with the passage b' , and an exit-flue in the transverse wall, substantially as described.

2. The furnace provided with grate-bars, a boiler supported by said furnace, a transverse 85 wall a , a wall a' , forming a coking-oven and a combustion-chamber and having its front lower portion made wider than the main portion of the wall a' , a wall or slab in the combustion-chamber to form a passage b' , and a 90 flue or passage b in the wall a' to connect the coking-oven with the passage b' , substantially as described.

3. The furnace provided with a boiler and a transverse wall a , forming, with a wall of the 95 furnace, a flue or passage, combined with a wall a' to form coking-ovens a^3 and a central chamber, grate-bars in said coking-ovens and central chamber, a wall or slab to divide said central space into chambers $b' b^3$, and a passage b , connecting the coking-oven with the chamber b' , an exit flue or passage in the transverse wall, and a damper to control said exit-passage, substantially as described.

In testimony whereof I have signed my 105 name to this specification in the presence of two subscribing witnesses.

JOHN MITCHELL.
